CIRCUIT BREAKER

William H. Frank, Elwood T. Platz, and
Lawrence E. Fisher, Detroit, Mich.

Application January 8, 1938, Serial No. 183,953

16 Claims. (Cl. 200—116)

This application relates to circuit breakers.

Principal objects of the present invention are to provide a novel circuit breaker mechanism, details of which will be described upon reference 5 to the appended drawings. In these drawings,

Fig. 1 shows in elevation and in "on" position a circuit breaker having the novel mechanism hereof;

Fig. 2 is an end section on line 2—2 of Fig. 1; 10 Fig. 3 is an exploded view showing details of the mechanism;

Fig. 4 shows the breaker in the "off" position;

Fig. 5 shows the breaker just after overload release and just before the parts are reset automatically in "off" position following such release; 15

Fig. 6 shows the casing per se in elevation;

Fig. 7 is a section on line 7—7 of Fig. 1.

A circuit breaker of the type under consideration generally comprises a spring actuated mechanism and a handle for providing manual actuation thereof, with the parts so arranged that the handle may be moved manually to cause the breaker mechanism to move to and from "on" and "off" positions with a snap action, to close and open the circuit, and with the parts also so arranged that on a circuit abnormality, such as overload, a circuit current responsive overload release latch (a bimetal warping element) will warp and destroy a latched connection between parts of the mechanism so that the spring of the mechanism will automatically cause movement of the mechanism out of "on" or closed circuit position and into an intermediate position to open the circuit, all without requiring or causing movement of the handle. If nothing exists to prevent further movement of the parts, as is normally the case and as is intended to be the case, the mechanism and handle will not come to rest in the intermediate position, but the spring will cause further movement of the mechanism into the "off" position and will also cause movement of the handle into such "off" position, thus automatically resetting the parts following overload release into an "off" position.

45 This application discloses a novel form of mechanism which is about to be described.

Referring to the drawings, it will be observed that Figs. 1—7 show an open top casing 10 on whose interior surfaces are formed guide slots 11 receiving guide lugs 12 of a contact bar 14, also known as a contact arm and as a contact operating arm, at an end of which is the movable contact 15. Projecting downwardly from the bar is an integrally formed tongue 16 to 55 which is secured a circuit current responsive

overload release latch 17 formed as a bimetal warping element. A flexible lead 18 connects the latch 17 to a binding part 19 to which a load conductor (not shown) is secured. Formed on the end of the contact bar 14 is a downwardly projecting lug 20 which is disposed within a hole 21 of a cradle or supplementary bar 22 at whose end are lugs 23 disposed within slots 24 of the contact bar with clearance between the cradle and the latch 17 being established by the provision of a large clearance slot 25 in the cradle. An end of the cradle passes through a hole 26 of a part 27 which is secured to the cradle, with the cradle insulated from such part by the provision of a suitable insulating liner 28 in the hole 26.

Side slots 29 of the cradle receive lugs 30 formed on a spring link 32 disposed within a coiled spring 33 whose end is seated in a spring socket 34 formed in the closed bottom of the 20 casing 10.

Disposed on the end of the contact bar adjacent the contact 15 is an insulation shield 36 provided with a hole 37 through which projects the contact 15 and this shield functions as an 25 arc quenching means operating on contact break between contact 15 and the stationary contact 38 formed on the terminal strap 39 connected by the screw 40 to the terminal connection clip 41 30 engaging the line conductor 42 which is shown 80 as a bus bar. A shield 43 of insulation material is provided on the terminal strap 39 to cooperate with the shield 36 for arc quenching purposes.

Passing through the opposite sides of the casing 10 and disposed slightly above the guide 35 slots 11 therein is an axle pin 59 which journals a handle 51 formed with downwardly projecting side flanges 52 and downwardly projecting end flanges 53. Projecting downwardly from the upper surface of the handle 51 and within and 40 spaced from the flanges 52—53 thereof is a downwardly projecting rib 54 whose lower edge engages the upper surface of the contact bar 14, as shown best in Figs. 1 and 2. The sides of the casing 10 dispose themselves within the spaces 45 between the rib 54 and the side flanges 52 of the handle.

The rib 54 contains a hole 55 for cooperation with a lug 56 formed from and projecting upwardly from the contact bar 14 for purposes 50 later to be described.

The operation of the mechanism will now be outlined. Normally the parts are in the "on" or closed circuit position of Fig. 1. The spring 33 has its line of action to the right of the engage- 55

ment of the rib 54 with the contact bar 14 and consequently tends to rotate the contact bar and cradle as a unit counterclockwise about the rib 54 as a pivot. Such tendency is inhibited by the engagement of the contact 15 on the bar 14 with the fixed contact 38 and consequently a pressure contact is established at this point by the spring pressure. The handle is maintained at rest by the spring pressure whose line of action is such that it tends to rock the handle clockwise on its axle 50 and such tendency is inhibited by the engagement of the right hand part of the handle with the right hand part of the casing as shown in Fig. 1.

15 If the handle is caused to rock counterclockwise by pressure on its left end, the parts will move to the position of Fig. 4. Pressure on the left end of the handle will rock the handle counterclockwise and move the end of rib 54 to 20 the right, across the line of action of the spring 33, first compressing and then releasing spring 33. Such spring will now tend to snap the unit comprising the bar 14 and the cradle 22 clockwise on rib 54 as a pivot. Such tendency will 25 cause the unit to move to open circuit position and come to rest in such position by virtue of the engagement of the left end of the contact bar 14 with a stop 57 formed on the interior of the casing and also by the engagement of the cradle 22 with a stop 58 also formed on the interior of 30 the casing; the parts thus will be seen to be at rest and maintained at rest by the spring pressure in the position of Fig. 4; the handle will also be maintained in its open circuit position by such 35 spring pressure, which tends at this time to rock the handle counterclockwise on its axle 50 and which tendency is inhibited by the engagement of the left end of the handle with the left end of the casing. In such handle movement, handle 40 rib hole 55 will pick up lug 56 for positive pull up on bar 14, if it be stuck at contacts 15-38.

To return the parts to the closed circuit position of Fig. 1 it is merely necessary to rock the handle clockwise by pressing down on its right end. The end of rib 54 will cross the line of action of spring 33 and the latter will thereupon snap the unit (14-17-22) counterclockwise on the end of rib 54 as a pivot to the closed circuit position of Fig. 1 with the unit and the handle 50 being maintained at rest in such position by the spring pressure.

It will be understood at this time that when the parts are in the "on" position of Fig. 1 or in the "off" position of Fig. 4 or are moving to 55 and from such positions, when caused so to do by manual movement of the handle, that at all times the contact bar 14, the bimetal element 17, and the cradle 22 are relatively immovable and move as a unit. Under such circumstances the 60 lower edge of the bimetal element 17 will constantly be in engagement with the upper edge of the part 27 positioned on the cradle 22.

If an overload occurs, the bimetal latch heats and warps with the result that such latch warps 65 to the left (Fig. 7) and off the upper edge of the part 27. This destroys the latch connection between the parts 14 and 22 and permits them to move relatively for the automatic release operation which will now be described.

70 When such warping of the bimetal element takes place and destroys the latch connection between the bar 14 (fixed to the bimetal element 17) and the cradle 22 and permits spring 33 to move the cradle independently of the bar and handle, spring 33 first moves cradle 22 upward

until such cradle engages the stop lug 58. Thereupon the cradle, and with it the bar 14, move around stop 58 and rib 54 as pivots to open the circuit between contacts 15 and 38, until the left end of the bar 14 engages the casing stop 57. 5 This effectively opens the circuit and this action takes place without the necessity of and without causing movement of the handle 51. Consequently, even if the handle be held against rocking, the mechanism can move to open circuit position 10 and consequently the breaker as a whole can properly be considered as having the trip free characteristic.

If the handle not be held, as is generally the case and as is intended to be the case, the parts 15 do not come to rest in the condition of Fig. 5 but move further to the position of Fig. 4 because of the spring pressure of spring 33. This pressure causes the handle to rock counterclockwise to the position of Fig. 4; in such movement the handle 20 hole 55 in its rib 54 picks up the lug 56 of the bar 14 and such bar moves with the handle up to the position of Fig. 4 where the parts come to rest, it being observed that, generally by this time the thermal element 17 has cooled and has reached 25 its normal position, that of being above and in engagement with the upper edge of the part 27.

Now having described a breaker mechanism hereof, reference will be had to the claims which follow for a determination of the invention 30 hereof.

We claim:

1. A circuit breaker mechanism comprising a contact bar, a supplementary bar, and a thermal latch, an overcenter spring bearing against the 35 supplementary bar, and an overcenter handle operatively connected to the contact bar, the bars being generally parallel and longitudinally extending, the spring and handle being generally transverse of and separated by the unit comprising the two bars, these being connected to 40 each other by the latch.

2. A circuit breaker mechanism comprising a contact bar, a supplementary bar, and a thermal latch, an overcenter spring bearing against the 45 supplementary bar, and an overcenter handle operatively connected to the contact bar, the bars being generally parallel and longitudinally extending, the spring and handle being generally transverse of and separated by the unit comprising the two bars, these being connected to 50 each other by a pivotal connection and by said latch.

3. In a circuit breaker, a contact bar and a supplementary bar, a stationary contact, the 55 contact bar being pivotally connected to the supplementary bar near one end of the contact bar, a circuit responsive latch latching the contact bar and the supplementary bar at the other end of the contact bar, said latch when unreleased causing the contact bar and supplementary bar to move together without relative movement and when released permitting the contact bar and supplementary bar to move relatively, the latch being supported on and by the 60 contact bar, and a spring engaging the supplementary bar between the points where the contact bar is connected to the supplementary bar, and, when the parts are in one position, causing the contact bar to move against the stationary 65 contact and towards latch held position with respect to the supplementary bar, and being operative to cause relative movement of the contact bar, the stationary contact, and the supplementary bar in the event of latch release. 70

4. In a circuit breaker, a contact bar and a supplementary bar, a stationary contact, the contact bar being pivotally connected to the supplementary bar near one end of the contact bar, a circuit responsive latch latching the contact bar and the supplementary bar at the other end of the contact bar, said latch when unreleased holding the contact bar and supplementary bar against relative movement and when released permitting the contact bar and supplementary bar to move relatively, the latch being supported on and by the contact bar, and a spring engaging the supplementary bar between the points where the contact bar is connected to the supplementary bar, the parts being so arranged that when they are in one position, the spring causes the contact bar to move against the stationary contact and towards the latch held position with respect to the supplementary bar, with the spring being operative to cause relative movement of the contact bar, the stationary contact, and the supplementary bar in the event of latch release, the parts also being so arranged that movement of the contact bar manually, when it is latched to the supplementary bar, causes movement of the spring to produce a snap action movement of the contact bar. 25
5. In a circuit breaker, a contact bar and a supplementary bar, a stationary contact, the contact bar being pivotally connected to the supplementary bar near one end of the contact bar, a circuit responsive latch latching the contact bar and the supplementary bar at the other end of the contact bar, said latch when unreleased causing the contact bar and supplementary bar to move together without relative movement and when released permitting the contact bar and supplementary bar to move relatively, the latch being supported on and by the contact bar, and a spring engaging the supplementary bar between the points where the contact bar is connected to the supplementary bar, and, when the parts are in one position, causing the contact bar to move against the stationary contact and towards latch held position with respect to the supplementary bar, and being operative to cause relative movement of the contact bar, the stationary contact, and the supplementary bar in the event of latch release, whereafter the latch relatches the contact bar and supplementary bar relatively. 50
6. In a circuit breaker, a contact bar and a supplementary bar, a stationary contact, the contact bar being pivotally connected to the supplementary bar near one end of the contact bar, a circuit responsive latch latching the contact bar and the supplementary bar at the other end of the contact bar, said latch when unreleased causing the contact bar and supplementary bar to move together without relative movement and when released permitting the contact bar and supplementary bar to move relatively, the latch being supported on and by the contact bar, and a spring engaging the supplementary bar between the points where the contact bar is connected to the supplementary bar, and, when the parts are in one position, causing the contact bar to move against the stationary contact and towards latch held position with respect to the supplementary bar, and being operative to cause relative movement of the contact bar, the stationary contact, and the supplementary bar in the event of latch release, the contact bar and the supplementary bar lying alongside one another, in an elongated unit, the breaker having a handle for engaging the contact bar and pivotally mounted between its ends on a pivotal axis transverse of the supplementary bar and contact bar. 5
7. A circuit breaker comprising a contact bar, a circuit condition responsive trip control element or latch having an inherent characteristic to move in response to circuit conditions, a movably mounted supplementary bar pivotally connected to said contact bar and positioned to be interlocked to the contact bar by the element when the latter is under normal circuit influence, or to be released thereby when the latter is under abnormal circuit influence, a spring acting directly on said supplementary bar, the contact bar being arranged to be moved manually, the contact bar, the element, and the supplementary bar comprising elongated members arranged so as to be generally alongside one another, and to move generally along with one another, together or relatively as the case may be, the spring and the manually engageable surface of the contact bar being on opposite sides of the group comprising the contact bar, the element, and the supplementary bar. 15
8. A circuit breaker comprising a contact bar, a circuit condition responsive trip control element or latch having an inherent characteristic to move in response to circuit conditions, a movably mounted supplementary bar pivotally connected to said contact bar and positioned to be interlocked to the contact bar by the element when the latter is under normal circuit influence, or to be released thereby when the latter is under abnormal circuit influence, a spring acting directly on said supplementary bar the contact bar being arranged to be moved manually, the contact bar, the element, and the supplementary bar comprising elongated members arranged so as to be generally alongside one another, and to move generally along with one another, together or relatively as the case may be, the spring and the manually engageable surface of the contact bar being on opposite sides of the group comprising the contact bar, the element, and the supplementary bar, the parts being so arranged that on the arising of a circuit abnormality, the element moves to release the supplementary bar from the contact bar, whereupon the spring moves the contact bar and supplementary bar relatively, after which the spring moves the parts so as to create once more an interlocking relation between the contact bar and the supplementary bar. 30
9. A circuit breaker including a movable contact, a stationary contact, a movable contact operating arm, a handle, and a thermally responsive latch for said arm, the handle and movable contact being so connected that movement of the handle in one direction causes the movable contact to withdraw from the stationary contact, and movement of the handle in the opposite direction causes the movable contact to approach the stationary contact, and a single spring for pressing the movable contact against the stationary contact when the parts are in circuit closed position, and for biasing the movable contact away from the stationary contact when the arm is released by the latch, the spring being connected to the contact operating arm free and independently of the handle, through a supplementary bar alongside the contact operating arm and latched thereto by the latch, with the handle directly and constantly engaging the contact operating arm which carries the latch. 35

- 50
- 55
- 60
- 65
- 70
- 75

10. A circuit breaker including a movable contact, a stationary contact, a movable contact operating arm, a handle, and a thermally responsive latch for said arm, the handle and movable contact being so connected that movement of the handle in one direction causes the movable contact to withdraw from the stationary contact, and movement of the handle in the opposite direction causes the movable contact to approach the stationary contact, and a single spring for pressing the movable contact against the stationary contact when the parts are in circuit closed position, and for biasing the movable contact away from the stationary contact when the arm is released by the latch, and for producing snap movement of the movable contact following movement of the handle, the spring being connected to the contact operating arm free and independently of the handle, through a supplementary bar alongside the contact operating arm and latched thereto by the latch, with the handle directly and constantly engaging the contact operating arm which carries the latch.
11. A circuit breaker including a movable contact, a stationary contact, a movable contact operating arm, a handle, and a thermally responsive latch for said arm, the handle and movable contact being so connected that movement of the handle in one direction causes the movable contact to withdraw from the stationary contact, and movement of the handle in the opposite direction causes the movable contact to approach the stationary contact, and a single spring for pressing the movable contact against the stationary contact when the parts are in circuit closed position, and for biasing the movable contact away from the stationary contact when the arm is released by the latch, the spring being connected to the contact operating arm free and independently of the handle, through a supplementary bar alongside the contact operating arm and latched thereto by the latch, with the handle directly and constantly engaging the contact operating arm which carries the latch, the latch being formed as an extended part of the arm, the arm and latch together comprising a unit having no fixed pivotal mounting but mounted on and by the handle.
12. A circuit breaker including a movable contact, a stationary contact, a movable contact operating arm, a handle, and a thermally responsive latch for said arm, the handle and movable contact being so connected that movement of the handle in one direction causes the movable contact to withdraw from the stationary contact, and movement of the handle in the opposite direction causes the moveable contact to approach the stationary contact, and a single spring for pressing the movable contact against the stationary contact when the parts are in circuit closed position, and for biasing the movable contact away from the stationary contact when the arm is released by the latch, and for producing snap movement of the movable contact following movement of the handle, the spring being connected to the contact operating arm free and independently of the handle, through a supplementary bar alongside the contact operating arm and latched thereto by the latch, with the handle directly and constantly engaging the contact operating arm which carries the latch, the handle being of the push-manipulation type and so constructed and the parts being so connected that snap movement of the contact operating arm, caused by the spring and initiated by move-
ment of the handle, will not be restrained on normal manipulation of the handle.
13. In a circuit breaker, a circuit responsive releasable latch, a stationary contact, a contact bar and a supplemental bar, the bars being pivotally interconnected near one end, and releasably interlocked relatively at the other end by said latch, the latch being supported on and by the contact bar, and a spring engaging the supplemental bar between the points where the bars are relatively interconnected, the parts being so arranged that when they are in one position, the spring biases the contact bar against the stationary contact and towards latch held position with respect to the supplemental bar, with the spring being operative to bias the contact bar to move relative to the stationary contact and the supplemental bar in the event of latch release.
14. In a circuit breaker, a circuit responsive releasable latch, a stationary contact, a manually actuatable contact bar and a supplemental bar, the bars being pivotally interconnected near one end, and releasably interlocked relatively at their other end by said latch, the latch being supported on and by the contact bar, and a spring engaging the supplemental bar between the points where the bars are relatively interconnected, the parts being so arranged that when they are in one position, the spring biases the contact bar against the stationary contact and towards latch held position with respect to the supplemental bar with the spring being operative to bias the contact bar to move relative to the stationary contact and supplemental bar in the event of latch release, the parts also being so arranged that movement of the contact bar manually, when it is latched to the supplementary bar, causes movement of the spring to produce a snap action movement of the contact bar into its final resting places in circuit open and circuit closed positions.
15. A circuit breaker mechanism comprising a contact bar, a supplementary bar, and a thermal latch, an overcenter spring bearing against the supplementary bar, and an overcenter handle operatively connected to the contact bar, the bars being generally parallel and longitudinally extending, the spring and handle being generally transverse of and separated by the unit comprising the two bars, these being connected to each other by the latch, the latch being carried by one of the bars, and means for restraining undesired relative movement of the two bars comprising a lug on one of them at all times disposed in a hole in the other.
16. A circuit breaker mechanism comprising a contact bar, a supplementary bar, and a thermal latch, an overcenter spring bearing against the supplementary bar, and an overcenter handle operatively connected to the contact bar, the bars being generally parallel and longitudinally extending, the spring and handle being generally transverse of and separated by the unit comprising the two bars, these being connected to each other by a pivotal connection and by said latch, the latch being carried by one of the bars, and means for restraining undesired relative movement of the two bars comprising a lug on one of them at all times disposed in a hole in the other.
